TELEVISION TRANSMITTER

Kurt Schlesinger, Berlin, Germany, assignor, by
mesne assignments, to Loewe Radio, Inc., a
corporation of New York

Application January 22, 1936, Serial No. 60,295
In Germany December 21, 1934

1. Claim. (Cl. 178—7.6)

Television transmitters for the transmission of films according to the interlaced scanning method have already been described in earlier applications. By this designation there is understood a method of scanning images which consists in the fact that one and the same image is scanned not merely once but a plurality of times with a correspondingly smaller number of lines, and these different scanning phases are transmitted successively, staggered in relation to each other to the extent of one line. In the application Ser. No. 36,008 which matured into Patent No. 2,186,931, Jan. 9, 1940, the applicant has set forth as means for obtaining an interlaced scanning of this kind a special, new-type double-spiral disc, characterised by the fact that at the point of connection of the two spirals the radial advance is omitted once to the extent of the width of one line. It was shown there that a double-spiral disc of this nature in conjunction with a film moved in the opposite direction results in a scanning operation with one single repetition and displacement to the extent of the width of one line, whereby all movements are of a uniform kind.

In a later application Ser. No. 46,126, which matured into Patent No. 2,147,555, Feb. 14, 1940, covering a form of embodiment it was shown that to overcome the trapezoidal error resulting from the incongruity of the trapezoidal sectional area of a disc of this kind and the rectangular reproduction area of the original image it is necessary to employ an inclined optical system, which provides a congruent trapezoidal reproduction of the film. In a further application there was then combined with these methods the self-synchronising image-point method, which consists in the fact that at the edge of the image there requires to be disposed a white starting line, the light intensity of which exceeds that of the whitest portions of the image.

All of these single inventive ideas are insufficient for practical execution until a large number of control knobs have been furnished in a transmission system of this character, so that the very precise optical settings and adjustments may actually be performed in the practical operation. There will be described in the present application a transmitter of this kind which has these possibilities and for the comprehension of which the above remarks may serve as a preambule.

The novel features which I believe to be characteristic for my invention are set forth with particularity in the appended claim. My in-

vention, however, both as to its organization and method for operation together with further objects and advantages thereof may be best understood by reference to the following description taken in connection with the accompanying drawings in which in Fig. 1 there is shown the Nipkow disc, for instance the film picture twice over its area.

In Figs. 2 and 3 there are illustrated details of the transmitter mechanism with the novel features of my invention, Fig. 3 being a section of Fig. 2 along the line 3—3.

Referring now in particular to Fig. 1 there is shown the operation of the two-fold scanning of a film, which is moved evenly from the bottom towards the top. In this connection a scanning period is divided into six single positions 1—6. In the position 7 there is already situated a new film picture in the position assumed by the previously transmitted image in position 1. The double-spiral disc 8 is shown in the correct operative position in relation to the movement of the film 1—7. Its sectional area is designated 9. The scanning image points are entered over the movement of the film. They are connected with each other in broken lines by a curve 10. This curve represents a relaxation oscillation interrupted at the points 6—7 or 1. The height of this relaxation oscillation is equal to the height of the sectional area 9 and is designated h . In comparison therewith the height of the film image is designated H . In regarding Fig. 1 it will be apparent that the interlaced scanning will only be successful, that is to say—the two part-scannings of the image will only correctly register, when the height of the film reproduction H is greater to the extent of two lines than the height of the sectional area h on the double-spiral disc 8. Expressed as formula:

$$H = h + 2z \quad 40$$

Operations with a transmitter of this kind are, therefore, only possible if the scale of the optical reproduction between film and disc can be adjusted very finely until the above equation according to the invention has been fulfilled. In addition, however, a number of other conditions must be fulfilled as regards the position of the reproduction, which are enumerated in the following:

1. *Metric.*—The scale of reproduction must be such that the height of the reproduction exceeds the sectional area on the disc by the width of two image points.

2. *Parallax.*—The adjustment of a reproducing

55

area, which fulfils the first condition, must be finely adjustable in such fashion towards the top and the bottom that both towards the top and the bottom exactly one line of the reproduction 5 extends beyond the sectional area.

3. *Trapezium*.—The optical reproduction of the film area on the disc must be accompanied by a trapezoidal distortion, in which the angle between the inclined sides of the trapezium is exactly equal to the angle between two successive 10 radii of the Nipkow disc.

4. *Image phase*.—The point of connection between two successive film pictures during the movement of the Nipkow disc and the film must 15 coincide with the connecting point between the two spirals on the Nipkow disc exactly at that moment when the spirals replace each other in the scanning operation.

5. *Meridian condition*.—The perpendicular 20 line passing exactly through the centre of the image must at the same time cut the axis of the Nipkow disc. The movement of the film must be exactly parallel to this perpendicular line.

The transmitter illustrated in Fig. 2 not only 25 permits of the accomplishment of these five conditions, which in their entirety guarantee the transmission, without error, of the contents of the image according to the interlaced scanning method.

30 Figs. 2 and 3 show in side view and cross section a transmission device which permits of the adjustment of all of these conditions. The film, in the manner known per se, is conducted from a supply reel 11 over a conveying roller 12 and then enters the track 13. With this film track there is firmly connected a feed roller 14, so that the film always runs smoothly on to the slides 13. A take-up roller 15, which is also firmly connected with 13, takes up the film smoothly 35 and conducts it to a second conveying roller 16 firmly connected with the casing. Following thereon the film may be conducted through the sound device to the second supply reel. To fulfil the metric condition 1 the gate 13 is mounted on a pivot 17, which in turn belongs to a sliding member 18. This member 18 is capable of being displaced in elongated apertures 18' exactly 40 in the direction of the reproducing ray of light. The displacement is finely adjustable by 45 means of screws and spindles (not shown). The Nipkow disc 8 and the shutter diaphragm 20 are 50

driven by synchronising motors 8' and 20' respectively. By increasing the spacing between film and disc to project a gradually decreasing reproduction on 8, which may always be adjusted to be sharp by readjustment of the shiftable 5 lens 19.

To fulfil the second "parallax" condition there is employed a vertical spindle 21. The spindle 21 moves upwards and downwards a diaphragm 22 close the plane of the film 13. After, therefore, 10 the lighted image section has been correctly adapted in size and position to the sectional area of the disc its trapezoidal form must be adapted to that of the disc 8. For this purpose there is provided the journal 17, the centre-point of which 15 lays exactly in the plane of the film 13. The entire film track 13 may accordingly be turned about this journal 17 and finally the correct inclination once and for all fixed by the screw 23. In addition, however, according to the invention, the entire optical passage of the rays must be capable of being adjustably tilted in relation to the horizontal. This is possible in any case in the majority of machines employed for kinematographic projection. The inclination in relation to the horizontal embraces the slide 18 and the lens 19 in common, so that the light always remains co-axial to these parts. With these two possibilities of inclination there may be accomplished quantitatively any desired trapezoidal 30 distortion.

The fourth condition, "image phase", is fulfilled by the interposition of an excentrically mounted roller 24. The image mark is able to be made co-phasal with the jumping-over point 35 on the Nipkow disc 8 by adjusting the excentricity of 24.

I claim:

In a television transmitter an arrangement for exactly adjusting the position of the film gate 40 relatively to the scanning means, said arrangement comprising a member which is horizontally shiftable for adjusting the distance of the film gate from the scanning means, a film gate adjustably pivoted on said member for varying the 45 inclination of the film gate relatively to the lens system, and a diaphragm shiftable on the film gate in a direction parallel to said film gate for adjusting the effective borders of the film gate. 50

KURT SCHLESINGER.
